UNITED STATES PATENT OFFICE.

HARRY HERBERT ROE, OF PRETORIA, SOUTH AFRICA.

LOCK FOR METERS, &c.

1,343,851.

Specification of Letters Patent. Patented June 15, 1920.

Application filed November 1, 1919. Serial No. 335,050.

To all whom it may concern:

Be it known that I, HARRY HERBERT ROE, a citizen of the Union of South Africa, and a resident of Pretoria, Union of South Africa, have invented a new and Improved Lock for Meters, &c., of which the following is a full, clear, and exact description.

This invention relates to locks for a number of special purposes, as for instance locks for meters (water and gas), pressure gages, time recorders, handcuffs, motor car hoods, bicycles, and the like, and has for an object to provide an improved construction in which the parts are few in number and easily operated.

Another object of the invention is to provide a construction of lock, a single key operated member, and a single hand operated member.

20 A further object is to provide a lock with a manually actuated bolt held normally in a locked position and a key operated screw.

In the accompanying drawing:

Figure 1 is a side view of a water meter 25 with a lock embodiment shown applied thereto.

Fig. 2 is a view similar to Fig. 1, but showing the lock in an unlocked position.

Fig. 3 is a top plan view of the lock removed.

Fig. 4 is a section through Fig. 3 on line 4-4.

Fig. 5 is a top plan view of a locking lug embodying certain features of the invention.

35 Referring to the accompanying drawing by numerals, 1 indicates a water meter which is provided with a lid 2 hinged at 3. In order to hold the lid 2 closed and locked a lock 4 embodying the invention is connected to the meter 1 at a point substantially diametrically opposite the hinge 3. The lock 4 is constructed of three pieces, namely the bolt 5, the screw 6, and the locking lug 7. The lug 7 is formed with a threaded

45 aperture 8 and with an offset or shoulder 9. The side of lug 7 carrying the shoulder 9 is soldered or otherwise rigidly secured to the meter 1, or if desired it could be made integral therewith. The bolt 5 is provided

50 with an overlapping ear 10 positioned to extend over and bear against the top of lid

2 for locking the lid closed. The bolt 5 is also formed with a large bore 11 merging into a small bore 12 approximately the size of the aperture 8. The large bore 11 is 55 designed to accommodate the triangular shaped head 13 of screw 6 which screw has a threaded section 14 screwed into aperture 8.

In operation when the parts are in the 60 position shown in Fig. 1 and it is desired to unlock the lid 2 a suitable spanner key is inserted into the bore 11 and screw 6 is turned until the lower portion of the flat side 15 has been raised above the shoulder 9 after 65 which the bolt is manually turned to one side as shown in Fig. 2. A reverse operation will, of course, bring the parts to a locked position.

What I claim is:

70 1. A lock for meters and the like comprising a lug rigidly secured to said meter, said lug having an upstanding shoulder and a threaded aperture, a locking bolt having a flat portion adapted to interlock 75 with said shoulder, and a locking screw extending through said bolt and into said threaded aperture for normally holding the bolt interlocked with said shoulder and thereby in a fully locked position. 80

2. A lock for meters and the like comprising a lug secured to the meter, said lug being formed with a shoulder and a threaded aperture, a bolt having an ear, a portion adapted to interlock with said shoulder, and a large bore merging into a small bore, and a clamping screw formed with a polygonal shaped head arranged in said large bore and threaded portion extending through said small bore into said threaded 85 aperture for clamping the bolt against said lug so as to cause the interlocking portion of the bolt to interlock with said shoulder and be locked against turning thereby. 90

3. In a lock for meters and the like the 95 combination with a meter having a hinge and lid adapted to fit flatwise against the meter casing, of a lug rigidly secured to said meter casing formed with an upstanding shoulder and a threaded bore, said bore 100 being parallel with the face of the shoulder, and a bolt formed with a flat portion

adapted to fit against the face of said shoulder and an overhanging portion overlapping said lid when the same is closed and when the flat portion of the bolt is against 5 said shoulder, said bolt having a large bore in the upper part merging into a smaller bore in the lower part, and a locking screw

having a tool engaging head, said head being arranged in said large bore with the threaded end of the screw extending through the 10 small bore into the threaded bore of said lug.

HARRY HERBERT ROE.
